UNITED STATES PATENT OFFICE.

GEORGE B. HUFFINGTON, OF ST. LOUIS, MISSOURI.

PRINTER'S QUOIN.

SPECIFICATION forming part of Letters Patent No. 743,165, dated November 3, 1903.

Application filed December 6, 1902. Serial No. 134,067. (No model.)

To all whom it may concern:

Be it known that I, GEORGE B. HUFFINGTON, a citizen of the United States, residing in the city of St. Louis, in the State of Missouri, have invented certain new and useful Improvements in Printers' Quoins, of which the following is a full, clear, and exact description, reference being had to the accompanying drawings, forming part of this specification.

My invention relates to that class of printers' quoins composed of two wedge-shaped members placed face to face and adapted to be moved longitudinally with respect to each other for wedging action within a printer's chase to hold the form located therein.

The invention consists in features of novelty hereinafter fully described, and pointed out in the claim.

Figure I is a side view of my quoins in partially-extended position. Fig. II is a view of the quoins in closed condition and partly in section. Fig. III is a perspective view of one of the wedge members of the quoins. Fig. IV is a transverse section taken on line IV-IV, Fig. I. Fig. V is a cross-section taken on line V-V, Fig. I. Fig. VI is a perspective view of a key used to impart longitudinal movement to the quoins wedge members.

1 designates the wedge members of the quoins, each of which is provided with a head 2 at its widest end that contains a dovetail groove 3.

4 designates dovetail tongues extending longitudinally and centrally of the wedge members 1, each tongue terminating at the base of the dovetail groove 3 in the heads of the members. The dovetail tongue 4 of each wedge member operates in the dovetail groove 3 of the opposite mating member, and the members are thereby held together, while they are permitted to move longitudinally of each other with the tongues in riding contact during the extension or elongation of the quoins. In the outer ends of the heads 2 are cavities 5, located at the outer terminations of the dovetail grooves 3, and upon the point of each wedge member is an inturned lip 6, that enters the cavity in the head of the opposing member and serves to limit the movement of the wedge members when the quoins is in contracted condition, as seen in Fig. II, thereby preventing separation of the members when the quoins has been contracted. The lips 6 are

formed integral with the points of the wedge members, so as to form rigid parts thereof, and in the manufacture of the quoins members they 55 are provided with transverse grooves 7 in the ends of the dovetail tongues 4, that permit of the lips being made in a straight line, as seen in Fig. III, with the tongues and afterward bent inwardly on the lines of the transverse 60 grooves 7, as seen in Figs. I and II, in order that they will enter the cavity 5 in the head of the opposing member. At their point ends the wedge members 1 are provided with plain inclined guide-surfaces 8, (see Fig. III,) 65 against which the legs of the head of the opposing wedge member ride in the elongation and contraction of the quoins. Between the head of each wedge member and the inclined guide-surfaces 8 are rack-teeth 9, which are 70 designed to receive the engagement of a key 10, which is introduced between the wedge members and fitted to the rack-teeth, as seen in Figs. I and II. By rotating the key 10 in either direction, according to the movement 75 it is desired to impart to the wedge members of the quoins, the members are caused to ride against each other to either elongate or contract the quoins.

It is a circumstance of frequent occurrence 80 that in the use of printers' quoins the rack-teeth and the ends of the wedge members in a short time after the quoins are placed in use become upset to a material degree, causing burs or rough edges at the outer ends of 85 the teeth and at the ends, those of the teeth being produced by the tool and those at the ends by the printer striking them. After roughness of the ends of the teeth and the ends of the members has been produced in 90 the manner stated the continued use of the quoins causes injury to the surfaces of imposing-stone and press-bed on which they are placed by producing indentations therein to the great detriment of the surfaces mentioned, which as a consequence in time become unfit for use as a result of such wear. In order to obviate the injury to the imposing-stone and press-bed surfaces referred to, I form lugs 11 at the sides of the heads 2 of 95 the wedge members, which project from the sides of the quoins at its ends, serve to support the body of the quoins off of the surfaces mentioned, and prevent contact of the outer

ends or faces of the rack-teeth and the ends of the members with surfaces to injure them.

I claim as my invention—

5 A printer's quoins comprising a pair of wedge-shaped members having heads provided with dovetail grooves, a tongue extending longitudinally of each member to operate in said dovetail groove, lips integral with the point ends of said members at the termina-

tions of said dovetail tongues, said tongues 10 being provided with transverse grooves at the junction of said lips and said tongues, substantially as set forth.

GEO. B. HUFFINGTON.

In presence of—

E. S. KNIGHT,

N. V. ALEXANDER.
